FIG. 1

FIG. 2

FIGURE 1 is a perspective view of the food vending machine or similar article taken from the front and one side thereof, showing our new design; and

FIGURE 2 is a side elevational view thereof.

The undisclosed side of said vending machine is substantially the same in appearance as the side shown.

The rear of the vending machine is substantially flat and plain.

The bottom front panel is of a conventional pattern and the surface is illustrated in broken lines.

We claim:

The ornamental design for a food vending machine or similar article, as shown and described.
